UNITED STATES PATENT OFFICE.

ABNER J. SMITH, OF BILOXI, MISSISSIPPI.

EYEGLASS-HOLDER.

1,016,103.

Specification of Letters Patent.

Patented Jan. 30, 1912.

Application filed May 11, 1910. Serial No. 560,738.

To all whom it may concern:

Be it known that I, ABNER J. SMITH, a citizen of the United States, residing at Biloxi, in the county of Harrison and State 5 of Mississippi, have invented certain new and useful Improvements in Eyeglass-Holders, of which the following is a specification.

This invention relates to eyeglass holders and has for its object the provision of a 10 comparatively simple and inexpensive device of this character, capable of being readily attached to a coat, shirt waist or other garment, and by means of which a pair of eyeglasses or spectacles may be conveniently suspended from a garment when 15 not in use.

A further object is to provide an eyeglass holder having a hump or projection formed thereon and which bears against the bill of 20 a suspension hook and serves to prevent accidental displacement of the eyeglasses or other article suspended from said hook.

Further objects and advantages will appear in the following description, it being 25 understood that various changes in form, proportions and minor details of construction may be resorted to within the scope of the appended claim.

For a full understanding of the invention 30 and the merits thereof, reference is to be had to the following description and accompanying drawings, in which:

Figure 1 is a perspective view of an eyeglass holder constructed in accordance with 35 my invention, showing the same in position on the lapel of a coat; Fig. 2 is a perspective view of the holder detached; Fig. 3 is a front elevation of the same; Fig. 4 is a side view; Fig. 5 is a transverse sectional 40 view taken on the line 5—5 of Fig. 4.

Corresponding and like parts are referred to in the following description and indicated in all the views of the drawings by the same reference characters.

The improved eyeglass holder forming 45 the subject matter of the present invention is preferably formed from a single length of wire or other suitable material having an intermediate portion thereof bent upon 50 itself to produce a double strand suspension hook 5, the wire constituting one of the strands of the hook extending upwardly to produce a vertically disposed strand 7, and thence bent or coiled upon itself to produce 55 an eye 8, the wire being thence extended

laterally at the rear of the strand 7 to form a transverse arm 9 and thence bent or coiled to produce an eye 10, similar in construction to the eye 8 and preferably disposed in transverse alignment therewith, as 60 best shown in Fig. 3 of the drawings. The wire after the eye 10 is formed is extended downwardly to a point near the bend 6 of the hook to form a similar vertical strand 11, the wire being thence bent around the 65 base of the hook to form a loop 12, the wire forming the end of the loop 12 being extended rearwardly in contact with the lower end of the vertical strand 11 and the free end of said wire bent to produce a keeper 13. 70

The wire forming the mating strand of the hook 5 is extended upwardly at 16 through the loop 12 and between the vertical strands 7 and 11 to a point above the eyes 8 and 10 where it is bent or twisted 75 upon itself at 14 to produce a centrally disposed eye 15. The wire, after the eye 15 is formed is continued downwardly over the transverse bar 9 and thence bent inwardly in contact with said bar and the rear face of 80 the intermediate strand 16 to form a clamping finger 17, the wire after the clamping finger 17 is formed being bent laterally at 18 and continued downwardly to form an attaching member 19 adapted to engage the 85 keeper 13.

The wire forming the intermediate portion of the strand 16 is bent laterally to produce a hump 20 adapted to bear against the bill of the suspension hook and thus prevent 90 accidental detachment of the eye glasses or other article suspended therefrom.

Attention is here called to the fact that the transverse bar 9 bears against the rear 95 portions of the strands 7, 11 and 16, while the clamping finger 17 bears against the bar 9 and serves to hold the parts in assembled position. It will also be noted that the loop 12 encircles the vertical strand 7 100 and adjacent portion of the intermediate strand 16 so as to hold said strands in contact with each other.

The eyes 8 and 10, by contact with the surface of a garment assist in preventing 105 lateral tilting movement of the holder thereon. The eyes 8 and 10 may also be used to assist in retaining the holder in position on a garment by stitching said eyes to the garment, if desired.

Having thus described the invention, what is claimed as new is:

An eye glass holder formed of wire having a portion thereof bent to produce a two strand suspension hook, one of the strands of the hook being extended upwardly to form a vertical strand and thence bent to produce an eye, the material being thence extended across the rear of the vertical strand to form a transverse bar and bent upon itself to produce a second eye, the material after the second eye is formed being continued downwardly and coiled around the base of the suspension hook to produce a loop terminating in a laterally extending keeper, the second strand of the suspension hook being extended upwardly through the loop and thence extended laterally to pro-

duce a hump arranged opposite the bill of the hook, the wire after the hump is formed 20 being continued upwardly between the vertical strands and bent to form a third eye, the wire being thence continued downwardly and inwardly and bent to produce a clamping finger extending across and in 25 contact with the transverse bar, the wire after the clamping finger is formed being continued downwardly to form an attaching member for engagement with the keeper. 30

In testimony whereof, I affix my signature in presence of two witnesses.

ABNER J. SMITH. [L.S.]
